UNITED STATES PATENT OFFICE.

WILLIAM M. FOLBERTH, OF CLEVELAND, OHIO, ASSIGNOR TO THE FOLBERTH AUTO SPECIALTY COMPANY, OF CLEVELAND, OHIO, A CORPORATION OF OHIO.

WINDSHIELD CLEANER.

Original No. 1,424,890, dated August 8, 1922, Serial No. 348,175, filed December 29, 1919. Application for reissue filed September 18, 1922. Serial No. 589,000.

To all whom it may concern:

Be it known that I, WILLIAM M. FOLBERTH, a citizen of the United States, residing at Cleveland, in the county of Cuyahoga and State of Ohio, have invented certain new and useful Improvements in Windshield Cleaners, of which the following is a specification.

This invention relates to improvements in windshield cleaners and more particularly to motors and valve operating mechanism therefor.

An object of the invention is the provision of improved means for actuating the valves of an automatically operated fluid motor for the purpose of continuously operating a windshield cleaner when desired.

A further object of the invention is the provision of valve mechanism whereby the valves will be retained in one position under tension until the piston or movable member in the motor travels a predetermined distance in one direction when a definite force will be applied to the valve to move it to a second position.

A further object of the invention is the provision of a motor having a relatively large opening therein and a closure plate for said motor, said closure plate being provided with valve mechanism arranged on the inner side thereof, whereby the valve mechanism will be readily accessible when the closure plate is removed.

In the present application, I have also disclosed a windshield cleaner having a motor which is adapted to be placed interiorly of the windshield, and is provided with means for operating the cleaner element disposed exteriorly of the windshield. This construction, while disclosed in the present application, forms the subject matter of a divisional application, filed March 11, 1922, Serial No. 543,063.

Other objects and advantages of the invention will be apparent during the course of the following description.

In the accompanying drawings, wherein for the purpose of illustration is shown a preferred embodiment of my invention and wherein like numerals designate like parts throughout,

Figure 1 is a perspective view of my wind-

shield cleaner attached to the windshield of an automobile,

Figure 2 is a transverse sectional view on line 2—2 of Figure 1,

Figure 3 is a longitudinal sectional view on line 3—3 of Figure 1,

Figure 4 is an enlarged fragmentary longitudinal sectional view similar to that shown in Figure 3,

Figure 5 is a transverse sectional view taken on line 5—5 of Figure 4,

Figure 6 is a combined perspective view of the plates forming a portion of the valve operating mechanism,

Figure 7 is a perspective view of the valve operating lever,

Figure 8 is an enlarged longitudinal sectional view taken on a line at right angles to Figure 4,

Figure 9 is a similar view of the opposite end of the cylinder on the same line, and,

Figures 10, 11, 12 and 13 show modified forms of attaching brackets by means of which the cylinder may be secured to windshields of different construction.

Referring now more particularly to the drawings, the reference numeral 10 designates a cylinder provided upon one side with angular shoulders 11. These shoulders 11 receive corresponding angular ears 12, formed upon one side 14 of the bracket 13.

The bracket 13 comprises in general a U-shaped member, the opposite sides 14 and 15 of which are adapted to be disposed upon opposite sides of a suitable support, such as framing 16 which holds the windshield glass 17 in position. The bracket may be held against shifting with relation to the framing 16 by means of retaining screws 13' or the like.

In the forms shown in Figures 10 and 11, the bracket retains substantially the same form as that shown in Figures 1 and 2, with the exception of the fact that the base of the U is somewhat rounded. It will be obvious that in some makes of cars, it is not desirable to have the operating shaft of the cleaner extend above the upper surfaces of the framing 16. In each of the forms shown in Figures 10 to 13 inclusive, the operating shaft 18 extends through the framing 16, openings 14' and 15' being formed in the arms 14 and 15.

of the bracket and opening 16' being formed in the framing 16 of the windshield. In the forms shown in Figures 12 and 13, this construction is slightly deviated from, in that 5 the bracket has but a single arm 12' which is secured to the inner side of the framing 16.

The operating shaft 18 is mounted for oscillation in the cylinder 10 and is provided in its outer end with a transverse bore 19, 10 which receives a cleaning bar 20, the bar being held in position in the bore by means of a set screw 21 or the like. The lower end of the cleaner bar 20 is provided with a cleaning element holder 22, adapted to receive a 15 cleaning element 23. These parts are shown in the present disclosure as being similar to those shown and described in my co-pending application Serial No. 325,873, filed September 24, 1919. The inner end 24 of 20 the shaft 18 extends beyond the inner side of the cylinder 10 and is provided with a transversely disposed operating arm 25 by means of which the shaft may be manually oscillated.

25 Mounted upon the rock shaft 18, within the cylinder 10 is a segmental gear 26, secured to the rock shaft in any desired manner. Slidably arranged within the cylinder are a pair of spaced pistons 27 and 28, connected by a member 29. This member 29 is provided upon one side thereof with a rack 30, which engages the segmental gear 26 and has a longitudinal bore 31, threaded at its outer end to receive an externally threaded 35 plug 32 for a purpose hereinafter to appear.

The ends of the cylinder are closed by removable heads 33 and 34, the head 34 being provided with an extension 35. A plug 35' 40 is provided, having threaded engagement with the extension 35 and having formed therein a longitudinal port 36. The longitudinal port 36 communicates with a transverse port 37 which in turn communicates 45 with the internal bore 38 of a tubular member to which is attached a conduit 39 connected with a suitable source of suction as, for example, the intake manifold of the engine or a vacuum tank forming a portion of 50 the fuel feed of the engine. The port 36 is provided with a seat 40 which is normally closed by a needle valve 41.

This port communicates with the conduit 43, formed in the extension 35 and the conduit 43 in turn communicates with a groove 44 formed in a plug 45 having threaded engagement with the extension of the head 34. The plug 45 is provided with a longitudinal bore 46, connected with the groove 44 by 60 means of a transverse passage 47.

Formed upon opposite ends of the plug 45 are valve seats 48 and 49, adapted to receive valves 50 and 51 respectively, having a common stem 52. One end of the passage 46 65 of the plug 45 communicates with the in-

terior of the cylinder at the end 53 thereof, and the other one communicates with the conduit 54. This conduit 54 in turn communicates with a conduit 54' extending transversely of the head 34. 70

The conduit 54' is interrupted by a plug 55 having an annular groove 56, alining with the conduit and a central bore 57 formed in the end thereof adjacent the end 53 of the cylinder. The groove 56 and bore 57 of the plug are connected by means of a passage 58.

Plug 55 is seated in a bore 55' which extends entirely through the extension 35 and head 34 and is provided upon its inner end 80 with screw threads to receive an externally threaded plug 59 having a longitudinal bore extending throughout its length, as at 60. The outer end of the plug 59 and the inner end of the plug 55 are each provided with 85 a seat, these seats being designated by the numerals 62 and 63 respectively. The seats 62 and 63 receive valves 64 and 66 respectively, having a common stem 67 extending through the bore 60 of the plug 59. The 90 stems 52 and 67 of the valves are connected by a transverse member 68 to operate in unison.

The end of the bore 54' communicates with the bore 69 extending in a direction longitudinally of the cylinder. This bore in turn 95 communicates with the conduit 70 which opens at the end 71 of the cylinder.

Secured to the inner face of the head 34 is a substantially T-shaped plate 72, having 100 upstanding portions 73 formed at the end of each arm of the head of the T. These upstanding portions terminate in portions parallel to the main body of the plate, as at 74. That portion of the plate forming the 105 stem of the T is also provided with an upstanding portion 85, having a portion 76 at the free end thereof, parallel to and extending over the main body of the member 72. The portions 74 are provided upon opposite 110 sides thereof with notches 77 and 78 for a purpose presently to appear. The plate 72 may be secured to the head 34 in any desired manner. As shown, openings 79 are provided in the plate 72 for the reception of 115 screws 80 having threaded engagement with the head 34.

A yoke 81 is provided comprising a loop portion 82 having the ends of the loop outspread, as at 83, and terminating in parallel 120 portions 84, having formed therein notches 85. These parallel portions 84 are spaced apart a distance equal to the distance between the notches 77 of the plate 72. Formed in the opposite sides of the loop portions 82 are pairs of alined openings 86 and 87, for a purpose hereinafter to appear. 125

A second yoke 88 is provided, having a loop portion similar to that of the yoke 81 with the exception of the fact that the arms 130

89 of the loop are more widely spaced. The outer ends of the arms 89 of the loop diverge, as at 90, and terminate in parallel portions 91, spaced apart a distance equal to the distance between the notches 78 of the plate 72. The parallel portions are provided with notches 92, adapted to coact with the notches 78. Formed in the arms 89 of the yoke 88 is a pair of aligned openings 93, for a purpose which will presently appear.

As clearly shown in Figures 3, 4, and 5, the plate 72 is secured to the head 34 and the yokes 81 and 88 arranged upon opposite sides of the portions 74 thereof with the notches of the yokes engaging the notches 77 and 78. A transverse pin 94 extends through the openings 86 of the yoke 81 and a transverse pin 95 extends through the openings 93 of the yoke 88. The pin 94 receives one end 96 of a tension spring 97 and the pin 95 receives the other end 98 thereof. The openings 87 of the yoke 81 receive the transverse member 68 which communicates with the stems 52 and 67 of the valves.

An operating lever 99 is provided, having formed upon its end spaced members 100. These members are provided with notches 101 to receive the pin 95 upon opposite sides of the end 98 of the spring. The end of the lever 99 adjacent the spaced members 100 is provided with a notch 102 to permit passage of the spring end 98. The lever 99 is reduced as at 103, thus forming shoulders 104 adjacent the end bearing the spaced members 100. This reduced portion is of such size as to slide easily in the bore 105 of the plug 32, but the shoulders 104 cannot enter this bore. The free end of the lever 99 is downbent as at 106, to prevent its withdrawal through the bore 105 of the plug 32 and it extends within the recess 31 of the member 29.

The bore 55' is provided with an opening 107, communicating with the atmosphere. Valve seats 62 and 63 are arranged on opposite sides of this opening.

The operation of the device is as follows:

When the valves are in the position shown in Figure 8, the end 53 of the cylinder 10 is in communication with the source of suction through conduit 39, tubular member 38, passage 37, ports 36 and 40, groove 44, and bore 46. The opposite end 71 of the cylinders is in communication with the atmosphere through opening 107, bore 55', bore 57, passage 58, groove 56, conduit 54', and conduits 69 and 70. The pistons accordingly move in a direction toward the end 53 of the cylinder. When the pistons arrive adjacent the end 53, the plug 32 engages the shoulders 104 of the lever 99 and forces the lever toward the head 34. As soon as the lever has been moved to a point where a line drawn through the pins 94 and 95 passes between the pivotal point of the yokes

and the head 34, the yoke 81 is shifted by the spring 97 and the valves are shifted to engage the seats previously disengaged.

When the valves are in this position, the end 71 of the cylinder is in communication with the source of suction through passage 54, conduit 54', and conduits 69 and 70. The end 53 of the cylinder is in communication with the atmosphere through port 107, bore 55', and the longitudinal bore 60 of the plug 59. When the valves are in this position, the pistons 27 and 29 move toward the head 33. Arriving adjacent the head 33, the downbent end 106 of the lever 99 engages against the inner end of the plug 32 and the yoke 88 is moved away from the head 34. As soon as the yoke 88 has been moved sufficiently that a line drawn through the pins 94 and 95 lies beyond the pivot point of the yokes 81 and 88 from the head 34, the spring 97 actuates the yoke 81 and returns the valves to the position shown in Figure 8.

It will be seen that the valves are not actuated until they are given a positive thrust by the spring 97 and that consequently these valves cannot assume a position intermediate their seats. There is no movement whatever of the yoke 81 until the spring has been brought to such a position, as the actuation of the yoke is governed by the spring.

In assembling the device, attention is drawn to the construction of the lever 99. This lever can only be inserted into its position by moving it through a line nearly parallel with the yoke 88. This is caused by the fact that the spaced portions are of such size that the notches 101 retain their grip upon the pin 95, after the lever has been moved back to a position in which it engages against the base of the yoke. It will be obvious that this construction lends rapidity of assembly and that after the parts of the device are in assembled position, it is impossible for the lever 99 to become accidentally disengaged. The structure of the yokes 81 and 88 and the supporting plate 72 thereof is furthermore of such character as to allow the device to be readily assembled and disassembled. Attention is called to the fact that the limiting stop 76 for the shifted yoke 88 is formed integrally with the base plate 72.

It is to be understood that the forms of the invention herewith shown and described are to be taken as preferred examples of the same, and that various changes in the shape, size, and arrangement of parts may be resorted to without departing from the spirit of the invention or the scope of the subjoined claims.

Having thus described my invention, I claim:

1. Valve actuating mechanism for wind-

shield cleaners having a cylinder, a reciprocating piston, and means for connecting said cylinder to a source of suction, said valve actuating mechanism comprising a shiftable 5 valve, a pivoted valve supporting member, a spring connected thereto, a second pivoted member, said spring being connected to said second pivoted member, and means actuated by the movement of the piston for shifting 10 the end of said spring to opposite sides of the pivot point of the pivoted supporting member for actuating said valve supporting member.

2. In a motor for windshield cleaners, a 15 cylinder, a member reciprocable therein, means for alternately connecting opposite ends of the cylinder to a source of suction comprising a conduit, a valve arranged therein, a member connected thereto, a 20 pivoted yoke connected to said member, a spring connected at one end to said yoke, a second pivoted yoke, the opposite end of the spring being connected thereto, and means operated by the movement of the reciprocable member for shifting the second 25 named end of said spring to opposite sides of the pivot point of the first yoke.

3. In an operating motor for windshield cleaners, a cylinder, a reciprocating piston 30 mounted therein, a valve adapted to alternately place the opposite ends of the cylinder in communication with a source of suction, a valve supporting member mounted in said cylinder, said member being provided 35 with a pair of parallel arms having offset ends, said offset ends being provided with notches, a member having a pair of arms, the ends of which are received in said notches to pivotally support said member, a spring 40 having one end secured thereto, means connected with the free end of said spring for maintaining it under tension, and means operated by the movement of the piston to shift the free end of said spring to opposite 45 sides of the pivot point of said pivoted member for actuating the valve supporting member.

4. In an operating motor for windshield cleaners, a cylinder, a member reciprocable 50 therein, a valve to alternately place the opposite ends of the cylinder in communication with a source of suction, a supporting member secured to the cylinder, a yoke pivotally mounted thereon, said valve being connected to said yoke, a second pivoted 55 yoke mounted on said supporting member, a spring connected to said yokes, and means operated by the movement of the reciprocable member for shifting one end of said 60 spring to opposite sides of the pivot point of the first yoke for actuating the yoke and its associated valve.

5. In an operating motor for windshield cleaners, a cylinder, a reciprocating piston 65 mounted therein, a valve adapted to alter-

nately place the opposite ends of the cylinder in communication with a source of suction, a supporting member mounted in said cylinder, said member comprising a base portion, and a pair of substantially parallel 70 arms, said arms being provided with offset ends, said offset ends being provided with oppositely arranged notches, a pair of yokes arranged in said notches to pivotally support them, the valve being connected to one 75 of said yokes, a spring connecting said yokes, and means operated by the movement of the piston to shift the second yoke to opposite sides of the pivot point of said yoke 80 to which the valve is connected.

6. Valve actuating mechanism for windshield cleaners having a cylinder, a movable member therein, and means for connecting said cylinder to a source of suction, said valve actuating mechanism comprising a 85 shiftable valve, a valve supporting member comprising a pair of pivoted arms having their pivots arranged adjacent each other and their outer ends remote from each other, a tension spring connected to each of said arms adjacent their outer ends, means for operatively connecting said valve to one of said arms, and means actuated by the movement of the movable member for moving the other arm and shifting the spring to opposite 90 sides of the pivot of the first arm. 95

7. Valve actuating mechanism for windshield cleaners having a cylinder, a member adapted to be reciprocated in said cylinder by differential pressure, and means for connecting said cylinder to a source of suction, said valve actuating mechanism comprising a shiftable valve, a pair of pivoted yokes mounted in said cylinder, said yokes having their pivots arranged adjacent each other 100 and their outer ends remote from each other, a tension spring secured to each of said yokes adjacent the outer ends of the yokes, means for operatively connecting said valve to one of said yokes, and means actuated by 105 the reciprocation of said member for moving the outer end of the other yoke and shifting the spring to opposite sides of the pivot of the first yoke. 110

8. Valve actuating mechanism for windshield cleaners having a cylinder, a member adapted to be reciprocated in said cylinder by differential pressure, and means for connecting said cylinder to a source of suction, said valve actuating mechanism comprising 115 a shiftable valve adapted to establish communication between either end of said cylinder, arms pivotally mounted on said supporting member mounted in said cylinder, a pair of arms pivotally mounted on said supporting member, said arms having their pivots arranged adjacent each other and their outer ends remote from each other, a tension spring connected to each of said arms adjacent its outer end, means for operatively 120 125 130

- connecting said valve to one of said arms, and means operable by the reciprocation of said movable member for moving the outer end of the other arm and shifting the spring to opposite sides of the pivot of the first arm for actuating said arm and its associated valve.
9. Valve mechanism for windshield cleaners having a cylinder, a member adapted to be reciprocated in said cylinder by differential pressure, and means for connecting said cylinder to a source of suction, said valve mechanism comprising a valve adapted to place either end of said cylinder in communication with the source of suction, a supporting member mounted in said cylinder, said supporting member being provided with a pair of substantially parallel arms, a pair of yokes pivotally mounted on said arms, said pivots being arranged adjacent to each other and the outer ends of said yokes being arranged remote from each other, a spring having one end secured to each of said yokes adjacent its outer end, means for operatively connecting said valve to one of said yokes, and means operated by the reciprocation of the movable member for moving the outer end of the other yoke and shifting the spring to opposite sides of the pivot of the first yoke.
10. Valve actuating mechanism for windshield cleaners having a cylinder, a member adapted to be reciprocated in said cylinder by differential pressure, and means for connecting said cylinder to a source of suction, said valve mechanism comprising a shiftable valve adapted to connect either end of said cylinder to a source of suction, a supporting member mounted in said cylinder, said supporting member being provided with a pair of substantially parallel arms having offset ends, a pair of yokes pivotally mounted on opposite sides of said arms and extending in opposite directions, a spring having one end connected to each of said yokes adjacent the outer ends of the yokes, means for operatively connecting said valve to one of said yokes, and means for moving the outer end of the other yoke and shifting said spring to opposite sides of the pivot of the first yoke.
11. Valve mechanism for windshield cleaners having a cylinder, a movable member mounted in said cylinder, and means for connecting said cylinder to a source of suction, said valve mechanism comprising a shiftable valve adapted to place either end of said cylinder in communication with the source of suction, a supporting member mounted in said cylinder, said supporting member being provided with a pair of substantially parallel arms having offset ends, the opposite ends being provided with notches, yokes pivotally mounted in said notches and extending in opposite directions,
- a tension spring connected to said yokes adjacent their outer ends, means for operatively connecting said valve to one of said yokes, and means operated by the movement of said member for moving the outer end of the other yoke and shifting the spring to opposite sides of the pivot of the first yoke.
12. Valve mechanism for windshield cleaners having a cylinder, a movable member mounted in said cylinder, and means for connecting said cylinder to a source of suction, said valve mechanism comprising a shiftable valve adapted to place either end of said cylinder in communication with the source of suction, a supporting member mounted in said cylinder, said supporting member being provided with a pair of substantially parallel arms having offset ends, the offset ends being provided with notches, yokes pivotally mounted in said notches and extending in opposite directions, a tension spring connected to said yokes adjacent their outer ends, means for operatively connecting one of said yokes to said valve, means operated by the movement of said member for moving the outer end of the other yoke and shifting the spring to opposite sides of the pivot of the first yoke, and means carried by the said supporting member to engage the first yoke to limit its movement.
13. Valve mechanism for windshield cleaners having a substantially air-tight casing, an actuating member mounted in said casing and adapted to be actuated by differential pressure, means for connecting said casing to a source of suction, said valve mechanism comprising a shiftable valve adapted to place the interior of said casing on opposite sides of said member in communication with the source of suction, a pair of pivoted arms mounted in the casing, said arms having their pivots arranged adjacent each other and their outer ends remote from each other, means for operatively connecting said valve to one of said arms, a tension spring secured to each of said arms adjacent the outer ends of said arms, and means operable by the movement of said actuating member to move the outer end of the other arm and shift said spring to opposite sides of the pivot of the first arm.
14. A motor for windshield cleaners comprising a cylinder having a relatively large opening therein through which access may be had to the interior of said cylinder, a closure plate adapted to be secured in position over said opening, said closure plate being provided with a pair of passages, one of which is open to the atmosphere, a conduit connecting the other passage to a source of suction, a piston in said cylinder adapted to be reciprocated by differential pressure within the cylinder, valve seats in each of said passages in said closure plate, valves cooperating with said seats, valve actuating

- mechanism carried on the inner side of said closure plate, and means operated by the movement of the piston for controlling said valve actuating mechanism to alternately place each end of said cylinder in communication with said conduit and the opposite end in communication with the atmosphere.
15. A motor for windshield cleaners comprising a cylinder having a relatively large opening therein through which access may be had to the interior of said cylinder, a closure plate bored to provide therein a pair of passages, one of which is open to the atmosphere, a conduit connecting the other passage to a source of vacuum production, means for securing said closure plate in position over said opening, a piston in said cylinder adapted to be reciprocated by differential pressure within the cylinder, valve seats adjacent each of said passages bored in said closure plate, valves cooperating with said seats, valve actuating mechanism carried on the inner side of said closure plate, and means operated by the movement of the piston for controlling said valve actuating mechanism to alternately place each end of said cylinder in communication with said conduit and the opposite end in communication with the atmosphere.
- 30 16. A motor for windshield cleaners comprising a cylinder having a relatively large opening therein through which access may be had to the interior of the cylinder, a closure plate adapted to be secured in position over said opening, said closure plate being provided with a pair of passages, one of which is open to the atmosphere, a conduit connecting the other passage to a source of suction, a manually operable control valve for controlling said passage connected to said conduit, a piston in said cylinder, valve seats formed in each of said passages in said closure plate, valves cooperating with said seats, elastically controlled valve actuating mechanism carried on the inner side of said closure plate and adapted to be locked in each of two positions against the resistance of the said elastic means, and means operated by the movement of the piston for shifting the said valve actuating mechanism whereby said elastic means will become effective to shift the said valves from one position to their opposite position.
17. A motor for windshield cleaners comprising a cylinder having a relatively large opening therein through which access may be had to the interior of the cylinder, a closure plate adapted to be secured in position over said opening, said closure plate being provided with a pair of passages, one of which is open to the atmosphere, a conduit connecting the other passage to a source of suction, valve mechanism for controlling said passages, a piston in said cylinder, valve seats formed in each of said passages in said closure plate, said valve mechanism cooperating with said seats, elastic means for controlling the movement of said valve mechanism whereby said valve mechanism will be held in its respective limits of movement, under tension, and means operated by the movement of the piston for shifting the said elastically controlled means whereby to operate the valve.
18. A motor for windshield cleaners, comprising a substantially air-tight casing having a relatively large opening therein through which access may be had to the interior of said casing, a closure plate adapted to be secured in position over said opening, said closure plate being provided with a pair of passages, one of which is open to the atmosphere, a conduit connected to the other passage, an actuating member mounted in said casing and adapted to be operated by differential pressure, valve mechanism to control the connection of said passages and said casing, valve actuating mechanism carried on the inner side of said closure plate, and means controlled by the operation of said actuating member to move said valve actuating mechanism, whereby said valve mechanism is shifted to alternately place said casing on opposite sides of said actuating member in communication with said conduit and the atmosphere.

In testimony whereof, I affix my signature in the presence of two witnesses.

WILLIAM M. FOLBERTH.

Certificate of Correction.

It is hereby certified that in Reissue Letters Patent No. 15,502, granted December 5, 1922, upon the application of William M. Folberth, of Cleveland, Ohio, assignor to The Folberth Auto Specialty Company, of Cleveland, Ohio, a Corporation of Ohio, for an improvement in "Windshield Cleaners," an error appears in the printed specification requiring correction as follows: Page 4, line 123, claim 8, strike out the words "arms pivotally mounted on said supporting" and insert instead the syllable and words *der and the source of suction, a supporting;* and that the said Letters Patent should be read with this correction therein that the same may conform to the record of the case in the Patent Office.

Signed and sealed this 9th day of January, A. D., 1923.

[**SEAL**]

KARL FENNING,

Acting Commissioner of Patents.
